UNITED STATES PATENT OFFICE.

MARTIN N. DIALL, OF TERRE HAUTE, INDIANA.

DESIGN FOR A HEATER FOR CURLING-IRONS.

SPECIFICATION forming part of **Design No. 26,328**, dated November 24, 1896.

Application filed October 19, 1896. Serial No. 609,374. Term of patent 7 years.

To all whom it may concern:

Be it known that I, MARTIN N. DIALL, a citizen of the United States, residing at Terre Haute, Indiana, have invented and produced 5 a new and original Design for a Heater for Curling-Irons, of which the following is a specification, reference being had to the accompanying drawing, illustrative of the same.

In the accompanying drawing is depicted 10 in side elevation, partly sectional, a curling iron heater embodying my design.

My invention relates to devices employed to support curling irons in such position in relation to a gas jet as to be heated thereby,— 15 and consisting of a receptacle for the curling iron, a foot adapted to be seated upon the burner, and a supporting stem connective of the foot and the receptacle.

The leading characteristics of a curling iron 20 heater embodying my design are that the foot, support, and receptacle, are all formed of a

single continuous piece of wire, one end of the wire being coiled into spiral form to constitute the foot, *a*,—the intermediate portion of the wire constituting the support, *b*,—and 25 the other end of the wire being coiled into spiral form to constitute the curling iron receptacle, *c*, the axis of the receptacle being perpendicular to the axis of the foot.

The free or outer end of the receptacle, *c*, 30 is partially closed.

What I claim is:

The design for a heater for curling-irons, substantially as herein shown and described.

In testimony that I claim the foregoing as 35 my invention I have hereunto signed my name this 9th day of October, 1896.

MARTIN N. DIALL.

In presence of—

E. MILLER,
J. S. POWER.
